[57] CLAIM

The ornamental design for a display holder for a wine bottle, as shown and described.

DESCRIPTION

FIG. 1 is a front, top, left side perspective view of a display holder of a wine bottle showing our new design;

FIG. 2 is a top plan view thereof;

FIG. 3 is a bottom plan view thereof;

FIG. 4 is a side elevation view thereof, the opposite side being a mirror image;

FIG. 5 is a front elevation view thereof;

FIG. 6 is a rear elevation view thereof; and,

FIG. 7 is a front perspective view thereof with the wine bottle shown in broken lines for illustrative purposes only and forming no part of the claimed design.
